VACUUM FIXTURE

Charles A. Van Dusen and Laurence W. Van Dusen, Escondido, Calif., assignors to Van Dusen Engineering Company, Escondido, Calif., a copartnership

Application July 17, 1950, Serial No. 174,292

6 Claims. (Cl. 248—206)

This invention relates to vacuum attachment devices and is directed particularly to improvements over the form of vacuum fixtures disclosed in the copending applications of Laurence W. Van Dusen, Serial No. 103,970, now Patent No. 2,634,076, filed July 11, 1949, and Serial No. 129,845, now Patent No. 2,634,077, filed November 28, 1949.

One of the principal objects of our invention is to provide vacuum attachment devices having improved means for supporting articles and devices without the necessity of any special supporting elements and without requiring that any holes be drilled in metal.

Another object of our invention is to provide a vacuum attachment device having an outer mounting plate formed of a plastic material which is suitable for the reception of wood screws.

Another object of our invention is to provide a vacuum attachment device employing the principle of operation set forth in the above-mentioned copending applications but embodying an impervious shell and mounting plate construction of improved durability and enhanced appearance.

Another object of our invention is to provide a device of the character described above employing a rubber-like diaphragm or suction member, the suction member being held in operative position by means of an impervious shell, the shell having an annular lip covering the outer periphery of the suction member.

A further object of this invention is to provide improved plastic structures having means permitting thick-walled elements to be molded or cast without excessive shrinkage and also permitting the entry of wood screws without splitting or fracturing the plastic.

Other objects and advantages of our invention it is believed will be apparent from the following detailed description of preferred embodiments thereof when read in connection with the accompanying drawings.

In the drawings:

Figure 1 is a side elevation showing a towel rack supported by a preferred embodiment of our invention.

Figure 2 is a side elevation, partly broken away, showing one of the vacuum attachment supports.

Figure 3 is a sectional elevation taken substantially on the line 3—3 of Figure 1.

Figure 4 is a sectional elevation taken substantially on the line 4—4 of Figure 3.

Figure 5 is a sectional elevation similar to that shown in Figure 3, but illustrating a modified embodiment of our invention.

Figure 6 is a sectional elevation similar to that shown in Figure 3, but illustrating a further modified embodiment of our invention.

Referring now to the drawings, the vacuum attachment device generally designated 10 is supported on the impervious surface 11 of a wall 12. The device includes a diaphragm or suction cup 13, preferably of synthetic rubber, having a peripheral contact portion 14 provided with an annular groove 15. Overlying the outer surface

2

of the diaphragm is a housing comprising a mounting plate or disk 24 and an annular shell 16 having a rim 17 which is received within the groove 15. An outer annular lip 18 is formed integrally with the shell 16 and covers substantially the entire outer periphery of the suction cup 13. The shell 16 has an inner rim 19 which overlies the outer periphery 20 of the rigid metallic plate 21 which is imbedded in the suction cup 13 and bonded thereto. An internally threaded metallic element 22 is secured centrally of the plate 21 by any convenient means such as, for example, by welding, and a tension screw 23 is threaded into this element 21. Mounted on the shell 16 is the mounting plate or disk 24 having a central aperture 25 through which the tension screw 23 extends. A metallic washer 26 rests on the disk 24 and engages the head portion 27 of the screw 23. An annular seat 28 is provided on the disk 24 for the reception of the inner rim 19 of the shell 16.

The vacuum attachment device 10 is mounted on the wall 12 in the same manner as described in the above-mentioned copending applications. Briefly, the disk 24 and shell 16 are removed from the diaphragm 13 by disconnecting the screw 23. The inner surface 29 of the diaphragm 13 is moistened and the diaphragm is then pushed flat against the surface of the wall 12 so that substantially all of the air is extracted between the surfaces 11 and 29. The annular shell 16 is installed with its rim 17 in the groove 15 and the disk 24 is then installed over the shell 16 so that the inner rim 19 of the shell is engaged in the seat 28 on the disk 24. The screw 23 is inserted through the washer 26 and a screw driver (not shown) is used to turn the screw relative to the metallic threaded element 22. This action serves to create a vacuum space 30 between the surfaces 11 and 29 and to apply sealing force against the peripheral contact lip 14 of the diaphragm 13. That portion of the contact lip which lies under the rim 17 is subjected to relatively high compressive forces, thereby effectively preventing entrance of air into the vacuum space 30. Moreover, since the inner rim 19 of the shell 16 overlies the outer periphery 20 of the metallic plate 21, a portion 31 of the diaphragm 13 is confined between the plate 21 and shell 16 and is also subjected to high compressive stresses with the result that air is prevented from leaking inwardly through this zone of compression. These two compression zones form, in effect, concentric leakproof gaskets preventing, with the impervious shell 16 and plate 21, entrance of air into the vacuum space 30.

The disk 24 is formed of molded or cast plastic material. It is to be understood that vacuum attachment devices made in accordance with our invention may be used in supporting various objects and devices such as towel racks, can openers, pencil sharpeners, etc. Therefore, it is desirable that a mounting plate be provided on the vacuum attachment device to which any one of several types of devices may be secured without requiring special attachment members or matching drilled holes. In the copending application of Laurence W. Van Dusen, Serial No. 129,845, now Patent No. 2,634,077, filed November 28, 1949, is disclosed a plywood mounting plate or disk with which may be used ordinary wood screws for securing a towel rack or the like to the attachment device. While such a plywood mounting plate is satisfactory for many applications, a plate or disk of plastic is often more advantageous, especially where the device is to be attached to a kitchen wall or fixture. The plastic materials are generally more durable and resistant to moisture, heat, solvents, and cleaning preparations and are available in a wide variety of attractive colors.

The structure of molded or cast plastic materials is such that it is extremely difficult to use ordinary wood screws without chipping or fracturing the plastic mate-

rial. In order to overcome this difficulty, the mounting disk 24 is provided with a plurality of longitudinal bores or holes 32. These holes are preferably about $\frac{3}{32}$ of an inch in diameter and spaced uniformly so that there is a minimum wall thickness between holes of approximately $\frac{1}{32}$ of an inch. The holes preferably extend to within about $\frac{1}{32}$ of an inch of the imperforate front mounting face 33. We have found that the holes 32 permit easy insertion of wood screws into the plastic and further that shrinkage and cavitation of such a thick section of plastic in the molding operation is prevented by use of cores to form the holes.

Wood screws 34 may thus be used to attach any desired device or article, and it is unnecessary to drill any matching holes or attach any special brackets for mounting such articles and devices on the vacuum attachment device. As shown in the drawings, a towel rack assembly including a bar 35 and brackets 36 is mounted on the device 10. Each of the brackets 36 may be provided with the usual mounting flange 37 and the wood screws 34 extend through openings provided in the flange. It is of course understood that other devices such as can openers, ice crushers, soap dispensers, towel dispensers etc., may be conveniently supported by attachment devices incorporating our invention.

In selecting plastic material for use as a mounting disk in such an attachment device it is necessary to consider that the material must not be so brittle as to crack or split when wood screws are inserted therein and yet it must be sufficiently hard to resist flow under the constant pressure applied at screw head 27. The cellulose acetate plastics are particularly well adapted for this use, but other plastics such as phenolics, acrylics, ureas, vinyls, etc., may be used, as will be readily apparent to those skilled in the art.

In the preferred embodiment of our invention illustrated in Figure 3, the shell 16 is formed of a plastic material which may be somewhat harder than that used for the mounting disk 24. The outer lip 18 is an important feature of our invention since it acts as a hood or cover member for the periphery of the resilient diaphragm 13, keeping it substantially sealed to prevent the accumulation of dust and dirt. The shell 16 may be stamped or formed of steel, if desired.

The modified form of our invention illustrated in Figure 5 is substantially similar to the device shown in Figure 3, with the exception that the shell 40 is formed integrally with the mounting disk 41. This unitary construction provides a structure of improved appearance. The incorporation of the smoothly curved surface 42 also prevents the accumulation of foreign matter.

The further modification of our invention illustrated in Figure 6 is substantially similar to that shown in Figure 5, but here a metal inner shell 45 is interposed between the plastic outer shell 40 and the diaphragm 13a, providing a more rugged assembly. This reinforcing shell 45 may be molded into the plastic shell; it may be a separate part secured to the plastic by friction set or other means; or it may be a separate part which remains so until the unit is mounted for use.

While we have shown and described our improved device in connection with a circular suction cup or diaphragm, it will be understood that the cup may be made in oval shape or even in a square or rectangular shape as desired, and that the cooperating parts of the device are shaped in similar manner.

Having fully described our invention, it is to be understood that we do not wish to be limited to the details herein set forth, but our invention is of the full scope of the appended claims.

We claim:

1. A suction type fastener comprising the combination of a resilient suction cup, an impervious shell having a continuous rim adapted to compress a continuous portion of the suction cup against a mounting surface, a

rigid plate imbedded within the central portion of the suction cup, a first screw element fixed to the rigid plate and protruding from the back face of the suction cup, a central plastic mounting plate overlying an inner rim on the impervious shell and being provided with a central aperture, said mounting plate having a plurality of voids therein to facilitate the insertion of wood screws, and a second screw element extending through the central aperture and cooperating with the first screw element to move the central portion of the suction cup in a direction away from the mounting surface.

2. A suction type fastener comprising the combination of: a circular resilient suction cup; an impervious annular shell having an annular rim adapted to compress an annular portion of the suction cup against a mounting surface; a rigid plate imbedded within the central portion of the suction cup; a first screw element fixed to the rigid plate and protruding from the back face of the suction cup; a central plastic mounting disk overlying an inner rim on the impervious shell, said mounting disk having an imperforate front mounting face and a relatively thick wall provided with a plurality of uniformly spaced longitudinal bores extending from the back of said plate to a position adjacent said front mounting face, whereby the insertion of wood screws is facilitated; and a second screw element extending through a central aperture in said disk and cooperating with the first screw element to move the central portion of the suction cup in a direction away from the mounting surface.

3. A suction type fastener comprising the combination of a resilient suction cup, an impervious shell having a continuous rim adapted to compress a continuous portion of the suction cup against a mounting surface, a rigid plate imbedded within the central portion of the suction cup, a first screw element fixed to the rigid plate and protruding from the back face of the suction cup, a central plastic mounting plate integral with said impervious shell and being provided with a central aperture, said mounting plate having a plurality of voids therein to facilitate the insertion of wood screws, and a second screw element extending through the central aperture and cooperating with the first screw element to move the central portion of the suction cup in a direction away from the mounting surface.

4. A suction type fastener comprising the combination of a resilient suction cup, an impervious shell having a continuous rim adapted to compress a continuous portion of the suction cup against a mounting surface and an integral outer lip closely conforming to and substantially completely covering the outer perimeter of said suction cup, a rigid plate imbedded within the central portion of the suction cup, a first screw element fixed to the rigid plate and protruding from the back face of the suction cup, a central plastic mounting plate integral with said impervious shell and being provided with a central aperture, said mounting plate having a plurality of voids therein to facilitate the insertion of wood screws, and a second screw element extending through the central aperture and cooperating with the first screw element to move the central portion of the suction cup in a direction away from the mounting surface.

5. A suction type fastener comprising the combination of a resilient suction cup, an impervious outer shell of plastic material having a continuous rim adapted to compress a continuous portion of the suction cup against a mounting surface, a reinforcing shell interposed between said outer shell and said suction cup, a rigid plate imbedded within the central portion of the suction cup, a first screw element fixed to the rigid plate and protruding from the back face of the suction cup, a central plastic mounting plate overlying an inner rim on the impervious shell and being provided with a central aperture, said mounting plate having a plurality of voids therein to facilitate the insertion of wood screws, and a second screw element extending through the central aperture and co-

operating with the first screw element to move the central portion of the suction cup in a direction away from the mounting surface.

6. A suction type fastener comprising the combination of a resilient suction cup; a housing overlying the outer surface of said suction cup, said housing comprising an impervious shell having a continuous rim adapted to compress a continuous portion of the suction cup against a mounting surface, and a central plastic plate extending from the central portion of said shell, said plate having a central aperture and a plurality of voids therein to facilitate the insertion of wood screws; a rigid plate imbedded within the central portion of the suction cup; and mechanical means operatively connecting the rigid plate with said housing for moving the central portion of the suction cup in a direction away from the mounting surface.
